HOSIERY FABRIC

Arnold Friedrich Verbeek, Oberlungwitz, Germany, assignor to Kalio Inc., New York, N. Y., a corporation of New York

Application December 31, 1935, Serial No. 56,888

1 Claim. (Cl. 66—173)

This invention relates to a new and useful improvement in hosiery fabric.

Some flat knitting machines are so designed that it is impossible to knit hosiery fabric of sufficient width for all purposes, particularly at the welt. Under such circumstances additional width can be obtained by knitting the welt of abnormally long loops which will increase the amount of stretch and thus produce, in effect, a wider fabric. This practice, however, decreases the elastic tension of the welt to an undesirable degree. The object of this invention is to supply by additional means the desired elastic tension without impairing the stretchability of the fabric which provides the extra effective width.

The invention is useful also to increase the elastic tension of the welt of very sheer fabric which possesses less inherent elastic tension.

A further object of the invention is to supply the desired elastic tension without materially affecting the appearance of the stocking and also without materially altering or complicating the knitting process. These results are obtained by weaving into the fabric which is otherwise made of silk or other suitable yarn, looped in the usual manner, an elastic weft thread, as will be described and as shown in the accompanying drawings, of which

Figure 1 is a diagrammatic view of the welt of a stocking blank in which a single elastic thread has been woven into occasional courses;

Fig. 2 is an enlarged cross-section of the welt of Fig. 1;

Fig. 3 is a diagrammatic view of a similar welt in which the elastic thread is arranged somewhat differently;

Fig. 4 is an enlarged cross-section of the welt of Fig. 3;

Fig. 5 is a diagrammatic view of a welt having still another arrangement of elastic threads;

Fig. 6 is an enlarged cross-section of the welt of Fig. 5; and

Fig. 7 is an enlarged view of a fragment of fabric showing a preferred manner of inserting the elastic thread.

In the welt shown in Figs. 1 and 2 the welt 1 has been turned and its attachment to the leg 2 completed. In that half 3 of the welt which forms the inside layer of the welt an elastic weft thread 4 has been woven into occasional courses, say in every fifth or tenth course, for example, depending upon the amount of elastic tension required. The weaving in of the elastic threads is preferably accomplished in accordance with the method disclosed in my co-pending application No.

3,892 filed January 29, 1935. When this method is followed the fabric shown in Fig. 7 will result. It will be noted from Fig. 7 and also Figs. 2, 4, and 6 that the elastic thread 4 passes through the sinker loops 5 and over the connecting needle 6 so that it appears only upon the back of the fabric, the silk or other yarn only showing upon the face 8 of the fabric. Therefore, the elastic threads lie within the completed welt and are thus protected from abrasion and from contact with the leg. Also the external appearance of the stocking is not altered to the extent it would be if the elastic threads appeared upon the outer surface thereof.

Another feature of this invention is that in each course in which it is woven the elastic thread terminates a few needles inside of the extreme edge of the fabric as shown at 9 and 10 so that it lies wholly within the fabric and is thus protected from injury when the stocking is seamed since the elastic threads do not enter the seam.

As will be evident from my copending application referred to, the insertion of such an elastic weft thread may be effected without altering or slowing up the regular knitting operation, a matter of great practical importance. Another valuable feature is that the breakage of the elastic thread will not in any way damage the fabric and cannot possibly produce runs or increase the tendency to run. In fact, the presence of the elastic thread adjacent the points of interlinkage of the needle and sinker loops supplies a run resisting feature not otherwise found in plain knitted fabric, since a run which starts above one of the weft threads cannot easily continue below it.

A somewhat different arrangement of elastic threads which may be employed when a somewhat greater elastic tension is desired is shown diagrammatically in Figs. 3 and 4. In this form of the invention the elastic thread 4 is woven as already described, into the loops of two adjacent courses and then again woven into two adjacent courses separated from the first two by a number of courses, say five or ten. This arrangement is shown in the upper half 11 of Figs. 3 and 4.

A further modification is shown in the lower half 12 of the same figures in which the elastic thread 4 is woven into three adjacent courses followed by a number of courses of plain fabric before the elastic insertion is again similarly repeated.

If desired part of the elastic insertion may be in the outer layer of welt fabric and part in the inner layer. This arrangement is diagrammati-

cally illustrated by Figs. 5 and 6 in which the elastic thread 4 is indicated as woven into the upper half 13 of the inner layer of the welt and the elastic thread 4' as woven into the lower half 5 14 of the outer layer of the welt.

Various other arrangements of interwoven elastic threads are obviously possible to meet different conditions. In all of them, however, will be found the features of an elastic thread in one 10 or more courses separated from a similar elastic thread insertion by a considerable number of courses to supply to the fabric an elastic tension greater than that inherent in the fabric itself but not of the strength required for a garter, 15 for example. Also in all of them the elastic threads terminate a short distance inside of the extreme edges of the fabric so that they are protected from injury when the stocking is seamed

and preferably run along the inner face of the fabric so that they are substantially concealed.

What I claim is:

A welt for a flat knitted full fashioned stocking which consists of fabric composed of courses the loops of which are the same in number and longer than those of adjacent leg courses so that the welt fabric is wider and less elastic than the leg fabric, said welt also having interwoven with each course of pairs of spaced courses an elastic 10 weft thread whereby the elastic tension of the welt is increased, said weft thread passing behind the needle loops of one of said each pair of courses and through the sinker loops of the other course of said pair interlinked therewith, said 15 weft being turned so that said elastic weft thread is exposed on the inside only of the welt.

ARNOLD FRIEDRICH VERBEEK.
